UNITED STATES PATENT OFFICE.

FRANK E. RICE, OF DETROIT, MICHIGAN, ASSIGNOR TO AMERICAN TAP BUSH COMPANY, OF DETROIT, MICHIGAN, A CORPORATION OF MICHIGAN.

ADJUSTABLE FLANGE-BUSHING.

1,194,664.

Specification of Letters Patent. Patented Aug. 15, 1916.

Application filed January 2, 1914. Serial No. 810,025.

To all whom it may concern:

Be it known that I, FRANK E. RICE, a citizen of the United States of America, residing at Detroit, in the county of Wayne 5 and State of Michigan, have invented certain new and useful Improvements in Adjustable Flange-Bushings, of which the following is a specification, reference being had therein to the accompanying drawings.

10 In the adjustment for bushes for receiving taps for drawing off the contents of metal packages, such as enameled or glass lined beer kegs and the like, it is advantageous that the parts be so disposed as to permit 15 adjustment for variation in the thickness of a receptacle wall.

This invention relates to a bushing for securing a tap in a metallic package and to an arrangement thereof whereby the bush 20 is adaptable for use with insulated and enameled or porcelain lined walls of varying thicknesses.

The invention consists in the matters hereinafter set forth and particularly pointed 25 out in the appended claims.

In the drawings, Figure 1 is a plan view of a portion of a package equipped with a bushing that embodies features of the invention; Fig. 2 is a view in detail and trans- 30 verse section of a portion of the package and the bushing.

As herein shown in preferred form, a package, illustrated as a beer keg, has an outer metallic shell 1 and an inner metallic 25 lining 2 separated by suitable insulating materials 3, such as cork or the like, and arranged to be enameled-on the inner face of the lining. A bushing body 4 that has a recessed outer face, is secured in an open- 40 ing through the outer wall 1 and the lining 3 with an exterior marginal flange 5 seated against the outer face of the outer lining. A nipple 6 is arranged in screw-threaded engagement with a central opening in the inner end portion of the bushing body with a slightly reduced inner portion 7 extending through a mating opening in the lining 2. The bore of the nipple is arranged to receive the tap tube and it has 45 on its outer end portion interrupted flanges 8 or the like holding means by which a tap may be secured when a tap tube is inserted to prevent leakage. The inner portion 7 of the nipple and the outer flange 5 of the body are both arranged to be brazed or

welded as indicated at 10 to respective metallic portions of the package with which they are in contact. As a result of this construction, a bushing is obtained which is adaptable to walls of varying thicknesses 60 so that a bush of a single pattern may be used not only for receptacles of different sizes but to receptacles of the same size whose walls may accidentally vary in thickness owing to the enameling and glazing 65 processes to which they are subjected. When secured in place it is to be understood that an enamel lining may be applied to the interior of a package and the exposed portion of the nipple.

Obviously, changes in the details of construction may be made without departing from the spirit of my invention and I do not care to limit myself to any particular form or arrangement of parts.

What I claim is:—

1. The combination with a liquid containing package having a wall formed with an outer metallic shell, an inner metallic lining, and insulating material separating the shell and lining, of a bushing having a cylindrical body provided with an exterior annular flange at the outer end and a recessed outer end face with a central opening through the inner end face, the outer exterior flange being adapted to bear against the outer metallic shell when the bushing is inserted in an opening through the wall of the package, and a nipple in screw threaded engagement with the central opening that is contained within the recess of the outer end face of the bushing, the inner end portion of the nipple having an exterior annular flange that bears against the lining on the interior of the package and prevents contact between any liquid contents of the package with the insulating material.

2. The combination with a liquid containing package having a wall with an apertured outer metallic shell, an inner metal lining having a smaller aperture aligned with that of the outer metallic shell and insulating material separating the shell and lining having an opening substantially coincident with the outer opening of the outer shell, of a bushing having a cylindrical body that fits closely in the openings through the outer shell and insulation and is provided with an exterior annular flange that bears against the marginal portions of the shell surround-

ing the openings, the outer face of the bushing having a deep recess communicating with a screwthreaded opening at the inner end of the bushing that is in register with 5 the opening of the inner lining, and a nipple threaded through the opening into the recess of the bushing and provided with an exterior annular flange on the inner end thereof that overlies the marginal portions

of the lining that surrounds the opening 10 therethrough.

In testimony whereof I affix my signature in presence of two witnesses.

FRANK E. RICE.
